DESIGN FOR A WALL BRACKET

Robert E. Haynes, Los Angeles, Calif., assignor to
Don Roberto of California, Los Angeles, Calif., a
partnership composed of Samuel Larner, Earl
Fifer, and Robert E. Haynes

Application November 1, 1944, Serial No. 116,086

Term of patent 3½ years

(Cl. D33—3)

To all whom it may concern:

Be it known that I, Robert E. Haynes, a citizen
of the United States and a resident of the city of
Los Angeles, in the county of Los Angeles and
State of California, have invented a new, orig-
inal, and ornamental Design for a Wall Bracket,
of which the following is a specification, refer-
ence being had to the accompanying drawing,
forming part thereof.

In the drawing:

Figure 1 is a front elevational view of a wall
bracket, showing my new design,
Figure 2 is a side elevational view,
Figure 3 is the opposite side elevational view,
Figure 4 is a top plan view, and
Figure 5 is a bottom plan view thereof.

I claim:

The ornamental design for a wall bracket, sub-
stantially as shown.

ROBERT E. HAYNES.
